[57] ABSTRACT

The opposite end walls of the erected shelter include at least one rigid panel, the lower edges of these panels being releasably received in a groove at the front and rear, respectively, of the shelter. A plurality of elongated rail members have L-shaped angle elements at each end which detachably engage over the upper edges of the panels and also the vertical braces secured thereto. A canvas sheet overlies the upper edges of the panels and the rail members to form the top and side walls of the structure. The edges of the canvas are anchored by means of flexible ropes. The flexible ropes that anchor the lower side edges of the canvas pass through openings in the floor which enable the shelter to be used as a fish house during winter months. A hinged lid is associated with each floor opening.

KNOCK-DOWN SHELTER

BACKGROUND OF THE INVENTION

1. Field of the Invention

This invention relates generally to knock-down shelters, and pertains more particularly to a shelter that will find especial utility as a portable winter fish house.

2. Description of the Prior Art

Various knock-down or collapsible shelters have heretofore been devised for use by ice fishermen. Many of these have proved to be too heavy and cumbersome for their intended purpose. Others have involved intricate assembling procedures, many requiring the use of various tools and metal fasteners. In wilderness areas, whether the shelter be used during the summer or winter months, it will be recognized that the shelter must be at times transported over appreciable distances. This poses a particular problem for ice fishermen, for frequently a good fishing lake is virtually inaccessible with the conventional type of vehicle. Even where the body of water can be reached by snowmobile, the snowmobile cannot transport heavy loads without sacrificing the carrying of other needed equipment. Also, the close proximity of trees with respect to each other and their low hanging branches further complicate the problem of transporting shelters that cannot be collapsed into compact and lightweight form.

SUMMARY OF THE INVENTION

In view of the shortcomings of the prior art, one important object of the present invention is to provide a knockdown shelter that is not only lightweight but which can be assembled without resort to screws, nuts, bolts or other fasteners requiring the use of tools.

Another object of the invention is to provide a shelter that will be sufficiently rigid, although still light in weight, so that it will resist relatively strong winds and at the same time provide sufficient insulation so that it can be used in sub-zero climates.

Still further, an object is to provide a knock-down or collapsible shelter that can be sold in kit form at a relatively low price, thereby encouraging its widespread use by various types of sportsmen during both winter and summer.

Briefly, my invention comprises flooring having a groove or slot at each end thereof which receive the lower edges of panels that are to constitute the end walls for the erected structure. Elongated rails have angle members at each end which overlie the upper ends of the end walls, thereby permitting a canvas or other flexible sheeting to be draped over the upper edges of the rigid walls and also the rails engaged therewith. The lower marginal edges of the canvas or other flexible material are suitably anchored by means of flexible ropes extending through slots or holes in the hinged lids when closed and the larger openings or holes when the lids are raised that enable the shelter to be employed as a fish house.

BRIEF DESCRIPTION OF THE DRAWINGS

FIG. 1 is a perspective view of my knock-down shelter when fully erected, a portion of one front wall panel being broken away so as to reveal the manner in which the lower edge of the fabric is anchored;

FIG. 2 is a perspective view of my shelter prior to draping the canvas thereover;

FIG. 3 is a sectional view taken in the direction of line 3—3 of FIG. 2 for the purpose of depicting the floor construction and the ice fishing holes provided therein, two intermediate portions having been removed to permit a larger scale to be used.

FIG. 4 is a sectional view taken in the direction of line 4—4 for the purpose of further illustrating the floor construction and one of the ice fishing holes contained therein;

FIG. 5 is a sectional detail taken in the direction of line 5—5 of FIG. 2 in order to illustrate the way in which the several elongated rails engage the upper edges of the end walls;

FIG. 6 is a sectional detail taken in the direction of line 6—6 of FIG. 2 to show the overlapping relationship of the vertical braces secured to the adjacent edges of the two front panels;

FIG. 7 is a sectional view taken in the direction of line 7—7 of FIG. 1, this view being on an enlarged scale and picturing to better advantage the way the canvas or other sheeting is anchored to the panels comprising the end walls, and

FIGS. 8 and 9 are fragmentary detail views depicting the two sizes of notches provided at the ends of the two outer rail members (FIG. 8) and the central rail member (FIG. 9).

DESCRIPTION OF THE PREFERRED EMBODIMENT

The knock-down shelter exemplifying my invention is illustrated in its erected condition in FIG. 1 and has been generally denoted by the reference numeral 10. The foundation for the shelter 10 constitutes two rectangular base frames 12a and 12b. Each frame 12 includes a pair of side strips 16, such as 1 x 4 inch wood, and end strips 18 of similar cross section. As best discerned from FIG. 3, the end strip 18 at the front (and also at the rear) has a spacer 20 secured thereto and a stop strip 22 confronting the spacer 20. In this way, an upwardly facing groove or slot at 24 is provided for a purpose presently to be made manifest.

At this time, attention is directed to two floor panels 26a and 26b. It will be appreciated that the floor panels 45 may be of whatever dimensions that are desired in order to provide the size of shelter 10 that is needed. Thus, the floor panels 26a and 26b may be of 4 x 8 foot plywood where two such panels are employed. Still further, if a somewhat smaller size of shelter 10 is desired, the floor paneling may constitute a single 5 x 8 foot or 5 x 10 foot piece of plywood. The particular size of floor panels 26a and 26b (or a single such panel) is unimportant as far as practicing the teachings of my invention. It will be appreciated, though, that the floor panels 26a and 26b are secured to the base frames 12a and 12b by screws 27. In order to fully collapse the shelter 10 it is preferred that the two-panel design be employed and that hinges 28 be provided at the juncture or butting edges of the floor panels 26a and 26b so that they can be folded against each other when they are to be transported. The pins can be removed from the hinges to facilitate one man handling. Beneath the panels 26a and 26b is applied a suitable insulation 29 such as a foamed or cellular plastic which can readily be secured in place with an appropriate adhesive, Styrofoam having been found satisfactory in actual practice.

Although my shelter 10 will find utility by sportsmen other than ice fishermen, the structure is also appealing to campers for instance, but will be described as a fish house. Accordingly, any preferred number of openings or holes 30 are formed in the panel 26a and a similar number in the panel 26b. Auxiliary framing 32 (much like the base frames 12a and 12b but on a smaller scale) provide a shoulder at 32 which permits a lid 34, there being one such lid for each hole 30, to lie flush with the panel 12a or 12b with which it is associated. Each lid has a pair of hinges 36 so that it can be raised from the lowered position illustrated in FIG. 2 to the raised condition that is visible in FIG. 1. Additionally, each lid is formed with a hole or slot at 37 for use when its lid 34 is closed, the reason for which will become clearer 15 hereinafter.

Playing an important role in the practicing of the present invention are end panels 38a, 38b, 38c and 38d. The panels 38a and 38b can be combined into a single panel and likewise the panels 38c and 38d into a single panel, such an arrangement being more practical where the shelter is fairly small. For the sake of discussion, however, it will be assumed that the panels 38a and 38b constitute the front wall of the completed shelter and the panels 38c and 38d the rear wall. As best viewed in FIGS. 3, each panel has a stop strip 40 attached thereto, the stop strip being disposed somewhat above the lower or bottom edge of the panel to which it is attached so that the lower marginal section of each panel can be releasably received in the previously mentioned groove 24. The panels 38a, 38b, 38c and 38d should be quite rigid and to impart additional rigidity to the $\frac{1}{4}$ inch thickness of plywood that has been found adequate, a pair of overlapping braces 42 and 44 are secured along the vertical edges that meet each other as far as the panels 38a and 38b are concerned at the front and the panels 38c and 38d at the back. As far as the outer edges of the panels 38a, 38b, 38c and 38d are concerned, braces 46 only at one side of each panel and along the remote vertical edge have proved adequate. In any case, screws 48 are used for permanently securing the braces 42, 44 and 46 to the panels.

In a shelter of the envisaged type, only one door 50 is necessary, the door being located in the front panel 38a in the illustrative instance. Although not entirely evident at this stage of the description, a plurality of holes 52 are drilled through the various panels 38a, 38b, 38c and 38d, these holes being spaced inwardly for a purpose presently to be made manifest.

Referring now to three cylindrical rods or rails 54a, 54b and 54c, it will be perceived that these rods or rails each have an L-shaped angle element 56 secured to each end thereof by means of appropriate screws 58. More specifically, the longer leg of each L-shaped element is the portion that is actually attached to the rod or rail 54a, 54b or 54c, as the case may be. The shorter legs are in a spaced relation with the ends of the members 54 to provide notches at 60a, 60b and 60c. The notches 60b, there being one such notch at each end of the rod or rail 54a, has a greater spacing existing between the shorter leg of the angle member 56 with respect to the end of the rod or rail 54b in order to receive therebetween the overlapping braces 42 and 44, as well as the thickness of the abutting panels 38a and 38b at one end of the shelter and 38c and 38d at the other end. Regarding the notches 60a and 60c, though, these notches are narrower (but both of same width)

inasmuch as only one brace 46 is employed along the outer edge of each panel 38. Hence, the notches 60a and 60c must only accommodate therein the panel thickness plus the thickness of one brace 46. Stated somewhat differently, if the braces constitute 1 $\times$ 2 inch strips, then the notch 60b at each end of the rail 38a would be $2\frac{1}{4}$ inches wide. One notch 60a (same as 60c) appears in FIG. 8 and can readily be compared with the notch 60b shown in FIG. 9.

10 While the goal of a shelter of this character is to have as much rigidity imparted thereto as possible, the rigidity militates generally against having a lightweight shelter. Thus, while the panels 38a, 38b, 38c and 38d are rigid, the rigidity being enhanced by reason of the braces 42, 44 and 46, the fabric now to be referred to not only makes the structure of considerably less weight but facilitates its erection. Consequently, a sheet of canvas 62, or other lightweight flexible material having water-proof properties, is draped over the several rails 54a, 54b and 54c as well as overlying the upper edges of the panels 38a, 38b at the front and the panels 38c and 38d at the rear.

While only one eyelet 64 is visible, this eyelet being seen in FIG. 1 through the broken away section of the panel 38b, it will be appreciated that any preferred number of eyelets 64, such as one or two per opening 30, may be affixed to the canvas 62 along each lower edge thereof. Likewise, whereas only one flexible tab 66 can be seen, the same number of tabs 66 would be 20 employed as the number of eyelets 64. The tabs 66 are stitched at 68 to the interior of the canvas 62. The tabs 66 in each instance has an eyelet 70. The lower end of a rope 72 is tied at 74 to each bottom eyelet 64. The upper end of the rope 72 is looped at 76 through the eyelet 70. As clearly perceived through the broken away section of the panel 38b in FIG. 1, the rope 72 passes through the particular fish hole 30, the lid 34 being actually held open by the rope 72 as it performs its anchoring function. However, when any of the lids 34 are closed, the ropes 72 then pass through the slots 37. Thus, where three fish holes or openings 30 are provided in the floor panel 26a and three in the panel 26b, there would be a minimum total of six anchoring cords or ropes 72.

45 Whereas the ropes 72 are adequate for anchoring the lower edges of the canvas 62, the side edges must be also anchored. Therefore, the invention has for an aim the provision of any preferred number of eyelets 78 in the side margins of the canvas 62. As better seen from FIG. 7, there is an elastic rope 80 associated with each eyelet 78, each elastic rope 80 having a metal hook 82 at the free end thereof. The elastic rope 80 is simply tied to the canvas 62 at the particular eyelet 78 with which it coacts. Unlike the rope 80, which is elastic, additional ropes 84, such as nylon, pass through the previously mentioned holes 52 formed inwardly with respect to the vertical and top edges of the various panels 38a, 38b, 38c and 38d. Here again, this feature can best be discerned from FIG. 7. An appropriately formed loop 86 is provided at the free end of each rope 84, such a loop being engageable by the particular hook 82 attached to the free end of the elastic rope 80. Through the agency of a simple knot 88 on the interior side of the panels 38a, 38b, 38c and 38d the rope 84, in each instance, is held in an anchored relationship with the panels constituting the end walls. To assist in such retention (and also to stop drafts), a washer 90 as well

50

55

60

65

can be employed, the knot 88 being sufficiently large so as not to pass through the hole in the washer 90. This rope loop provides a metal-free eyelet which avoids any protruding metal that would be apt to get bent.

Inasmuch as it is contemplated that my shelter 10 will prove adequate for winter use, an asbestos insert 92 is disposed in the canvas 62, having an opening 94 through which the smoke stack from the user's stove or heater can project.

The procedure to be followed in erecting or assembling my shelter 10 is exceedingly simple and straightforward. As already explained, no metal fasteners, such as nuts and bolts, are employed. When the user wishes to erect the shelter, he merely unfolds the two base frames 12a and 12b, together with their permanently attached floor panels 36a, 36b, so that they assume a planar relationship. At this stage, the grooves or slots 24 are available for receiving the lower edges of the panels 38a, 38b, 38c and 38d. Owing to the presence of the stop strips 40, there being one for each panel 38a, 38b, 38c and 38d, the marginal edge of each panel can be easily dropped into its respective groove 24. The groove 24 is deep enough so as to maintain the panels 38a, 38b, 38c and 38d in a vertical position. Then all that the user need do is to place the several braces 42, 44 and 46, taking care that the proper width of notch 60a, 60b and 60c is used. It will be appreciated that the rails 54a, 54b and 54c rest on the underlying structure, there being no fastening means resorted to. The shelter is then in readiness for having the canvas 62 placed thereover. The lower edges of the canvas 62 are tucked under the outermost side strips 16 of the base frames 12a and 12b so as to make the eyelets 64 and ropes 72 contained therein accessible through the holes 30 in the floor panels 26a and 26b. The user may then enter the shelter 10 via the door 50 if he chooses to do so at this time so as to thread each cord or rope 72 through the eyelet 70 contained in the tabs 66. He pulls the cord or ropes 72 taut in each instance and this likewise pulls the canvas 62 tightly over the rails 54a, 54b and 54c. Before doing this, he could have completed the anchoring of the margins of the canvas 62 containing the eyelets 78 through the simple expedient of engaging the hook 82 with the nearest loop 86, the elastic rope 80 stretching sufficiently to achieve this goal. The elasticity of the ropes 80 then pull the marginal edges tightly over the side and top edges of the several panels 38a, 38b, 38c and 38d.

Virtually an integral structure results. The panels 38a, 38b, 38c and 38d no longer can be disengaged from the grooves or slots 24 in which their lower marginal edges reside owing to the downward pull exerted by the overlying canvas 62. The canvas 62 in turn is held downwardly through the agency of the cord or ropes 72. Consequently, an exceedingly sturdy shelter results which is relatively air tight by reason of the overlying canvas 62 and the various anchoring ropes attached thereto. In other words, the cold ambient air has no real way in which to enter the confines of my shelter 10.

When the user wishes to collapse or knock-down the shelter 10, the steps are practiced in reverse order and the shelter can quickly be transported to a new location and then re-erected or stored, as the case may be. When storing or transporting the knock-down shelter 10, the floor panels 26a and 26b are reversely folded (or stacked if the hinge pins are removed) against each

other, the hinges 28 permitting this. Then, the several end panels 38a, 38b, 38c and 38d can be stacked on whichever base frame 12a, 12b is uppermost. The several rails 54a, 54b, and 54c can then be placed on top of the panels 38 and the canvas 62 folded to a partial degree so that it overlies the several rails 54 and preferably extends downwardly over the sides of the stacked panels 38. On the other hand, the canvas 62 can be rolled on the rails, if desired.

As already mentioned, the floor panels 26a and 26b can constitute a single panel. Also, the end panels 38a and 38b can constitute a single wall and the panels 38c and 38d also a second single wall. This will depend largely upon the size of the shelter 10 as to whether one floor panel or two are used and whether two or four end panels are employed.

I claim:

1. A knock-down shelter comprising a pair of rigid panels having upper, side and lower edges, base means constituting the floor of the shelter and providing a pair of upwardly facing grooves or slots at each end thereof formed in each instance by parallel vertical walls having a spacing approximately equal to the thickness of said panels for releasably receiving the lower edges of said panels therebetween so that said panels form the spaced end walls of the shelter, at least one pair of elongated rail members having their ends detachably engageable over the upper edges of said panels, a sheet of flexible material overlying the upper edges of said panels and said rail members to form the top and side walls of the shelter, with marginal portions thereof extending downwardly from said upper edges in a confronting relation with upper portions of said panels and inwardly from said side edges in confronting relation with side portions of said panels, first detachable fastening means connecting said marginal portions of said flexible sheet material to said panels at locations near their said upper and side edges, said flexible side walls having lower portions located adjacent said base means, said base means being formed with a plurality of fish holes therein, and second detachable fastening means extending from the lower portions of said flexible side walls upwardly through said holes to portions of said side walls located above said holes to connect said bottom portions of the side walls to said base means.

2. A shelter in accordance with claim 1 in which each panel has a marginally spaced horizontal strip for confronting the marginal portion of the floor adjacent the groove or slot in which its lower edge is received.

3. A shelter in accordance with claim 1 including an angle element at each end of each of said rail members, said angle element having horizontal sections for extending over the upper edges of said panels and downturned sections for confronting the outer marginal portions of said panels, said overlying flexible sheet material retaining said angle elements against said upper edges.

4. A shelter in accordance with claim 3 in which said downturned sections are parallel with the ends of said rail members so that the ends of said rail members confront inner marginal portions of said panels.

5. A shelter in accordance with claim 1 in which said panels have a plurality of holes spaced inwardly from their top and side edges, said first fastening means including a rope having an outer loop for each hole and an intermediate portion thereof extending through the hole with which it is associated, each rope being knot-

ted at its other end so as to anchor same with respect to the panel to which it is attached, said first fastening means further including a second rope for each hole anchored at one end to the marginal edge of said sheet materia' and having a hook element thereon at its other end engageable with the loop nearest thereto.

6. A shelter in accordance with claim 5 in which each of said last-mentioned ropes is elastic.

7. A shelter in accordance with claim 6 in which said second fastening means includes a plurality of additional ropes having one end anchored to said side walls adjacent the two bottom edges thereof, and means secured to said side walls above their said bottom edges for anchoring the other ends of said additional ropes to said side walls.

8. A shelter in accordance with claim 7 including an eyelet in said marginal edge of the sheet material for each elastic rope, said other end of each elastic rope being tied to one of said eyelets.

9. A shelter in accordance with claim 8 in which said side walls have a plurality of eyelets adjacent their two bottom edges, said other end of each of said additional ropes being tied to one of said bottom eyelets.

10. A shelter in accordance with claim 9 in which said means secured to said side walls above their said bottom edges includes a plurality of tabs secured to the inside surfaces of said side walls, each of said tabs having an eyelet for engaging a loop formed at said other end of each of said additional ropes.

11. A shelter in accordance with claim 10 including a lid hinged at one edge for closing each fish hole, said lids each having a slot extending inwardly from said one edge and said lids being held open by said additional ropes or said additional ropes passing through said slots when said lids are closed.

12. A knock-down shelter comprising a pair of rigid panels at each end thereof so that each pair of panels form an end wall of the shelter, said panels having upper edges, lower edges, vertical adjacent edges and outer vertical edges, overlapping braces extending along the adjacent vertical edges of each pair of said rigid panels, additional braces extending along the

outer vertical edges of said panels, base means providing upwardly directed slots or grooves at each end thereof for receiving therein the lower edges of said panels, a plurality of elongated rail members having an angle element at each end thereof, the two angle elements of one rail member forming a notch for receiving therein the upper ends of the overlapping braces at one end of said shelter and the upper ends of the overlapping braces at the other end of said shelter, additional rail members having angle elements forming additional notches of a size to receive therein the upper ends of the braces at the outer edges of said panels, a sheet of canvas overlying the upper edges of said panels and said rail members, and means anchoring portions of said canvas sheet to portions of said panels spaced from said upper edges and from said side edges thereof.

13. A shelter in accordance with claim 12 including means for anchoring additional portions of said canvas to said base means.

14. A shelter in accordance with claim 13 in which said base means includes a plurality of fish holes, said means for anchoring said additional portions of said canvas to said base means including cords or ropes extending upwardly from said additional portions of said canvas through said fish holes and connecting with portions of said canvas thereabove.

15. A shelter in accordance with claim 14 in which each of said anchoring means includes a rope.

16. A shelter in accordance with claim 15 in which the base means includes a plurality of fish holes, the ropes for the bottom edges extending upwardly through said fish holes and said panels having holes spaced inwardly from their side and top edges, the ropes for the side edges of said canvas passing through said last-mentioned holes.

17. A shelter in accordance with claim 16 in which said sides of the canvas have elastic ropes secured thereto having hook members at the free ends thereof and said ropes for the sides of said canvas having loops thereon engageable by the hooks on said elastic ropes.
